WATCH OR CLOCK MOVEMENT

Ferdinand Leo Ziebart, Winnipeg,
Manitoba, Canada

Application May 19, 1950, Serial No. 162,850

2 Claims. (Cl. 58—46)

1
This invention relates to timepieces, and more particularly to an improved and simplified watch or clock movement.

A main object of the invention is to provide a novel and improved movement for a timepiece, said movement being very simple in construction, providing a uniform distribution of wear on the working parts of the movement, and minimizing the possibility of overwinding the spring of the movement.

A further object of the invention is to provide an improved watch or clock movement which involves relatively inexpensive parts, which is reliable in operation, which is arranged so that overstressing of the driving spring is substantially avoided, and which provides a very compact assembly.

Further objects and advantages of the invention will become apparent from the following description and claims, and from the accompanying drawings, wherein:

Figure 1 is a front elevational view, partly broken away, of a clock employing the improved movement of the present invention,

Figure 2 is a vertical cross sectional transverse view taken through the clock of Figure 1,

Figure 3 is a cross sectional view taken on the line 3—3 of Figure 2,

Figure 4 is a cross sectional view taken on the line 4—4 of Figure 2,

Figure 5 is a cross sectional view taken on the line 5—5 of Figure 4,

Figure 6 is an enlarged cross sectional detail view taken on line 6—6 of Figure 4, and

Figure 7 is an enlarged fragmentary elevational detail view showing the ratchet means coupling the small driven gear of the improved movement with the hour and minute pointer operating gear trains, as employed in the clock of Figures 1 to 5.

Referring to the drawings, 11 generally designates a timepiece, illustrated as a clock, the clock being provided with a base 12 and a cylindrical body 13. Secured in the body 13 is the frame 14, said frame comprising respective parallel plate elements 15 and 16 connected by transverse rod elements 17. Secured to the forward ends of the rod members 17 is the face of a clock, shown at 18, the face 18 being peripherally flanged as shown at 19 and a transparent circular window 20 being secured within the flange, as shown. The back cover of the clock is designated at 21, said back cover being flanged at 22 and being fastened to the inside surface of the body 13 at the flange 22.

Rotatably mounted in the rear plate member 16

2
is a shaft element 23 which projects through an opening 24 in the rear cover plate 21 and which carries a handle 25. The shaft element 23 has a reduced forward portion 26 which extends through and is rotatably supported in the forward plate element 15. Secured on the shaft member 23 is a sleeve 27 and secured to the rear end of the sleeve 27 and to the shaft 23 is a relatively large gear 28. Designated at 29 is a cylindrical sleeve which is rotatably mounted on the sleeve 27, as by means of ball bearings 30. Secured to the forward end of the sleeve 29 is another relatively large gear 31, said gear 31 however being smaller than the large gear 28. Designated at 32 is a spiral spring whose inner end is secured at 33 to the sleeve member 29 and whose outer end is secured to a stud member 34 threadedly engaged in the peripheral portion of the large gear 28 and projecting toward the other large gear 31 in the manner shown in Figure 5, the spring 32 being formed with an end loop 35 which receives the inwardly projecting stud member 34.

Designated at 36 is a shaft member which extends parallel to the shaft member 23 and which is rotatably supported in the front and rear plate members 15 and 16. Rotatably mounted on the shaft member 36 is a sleeve 37 formed at its end portion with the respective relatively small gears 38 and 39 meshing respectively with the large gears 31 and 28, as shown in Figure 2. Secured on the forward end of the shaft 36 is a small gear 40.

The forward face of the gear 38 is formed with ratchet teeth 41 and rigidly secured on the shaft 36 is a ratchet disc 42 formed with ratchet teeth 43 facing the teeth 41 and interengageable therewith. Designated at 44 is a coil spring surrounding the portion of shaft 36 located forwardly of the ratchet disc 42 and bearing between said disc and with the plate member 15, as shown in Figure 6. From Figure 2 it will be seen that the spring 44 biases the ratchet disc 42 into engagement with the ratchet teeth 41 and hence couples shaft 36 to sleeve 37. Gear 38 therefore may drive shaft 36 clockwise, as viewed in Figure 4, but may be rotated freely counter-clockwise with respect to said shaft 36.

Secured to the plate member 15 is a bearing element 45 rotatably supporting a shaft 46 having rigidly secured thereon the respective gears 47 and 48, the gear 47 being relatively large and the gear 48 being relatively small, and the gear 47 meshing with the gear 40, as shown in Figure 2. Rotatably mounted on the forward end portion of the reduced shaft section 23 is a sleeve 49 to which is secured the minute hand 50. Secured to

55

the rear portion of sleeve 49 is a gear 51 which is relatively small and which meshes with the larger gear 47. Rotatably mounted on the sleeve 49 is a sleeve 52 on which is secured the hour pointer 53. Also secured to sleeve 52 is the relatively large gear 54 which meshes with the smaller gear 48, as shown in Figure 2.

The shaft 36 extends rearwardly through the cover plate 21 and carries a knurled knob 55. Knurled knob 55 enables the shaft 36 to be rotated counter-clockwise, as viewed in Figure 4, enabling the hour and minute pointers 53 and 50 to be manually set.

In operation, the shaft 23 is rotated by means of a handle 25 in a counter-clockwise direction, as viewed in Figure 3, causing the gear 28 to rotate counter-clockwise and causing the sleeve 37 to be rotated clockwise, as viewed in Figure 3, by the meshing engagement of gear 39 with gear 28. Gear 38 rotates gear 31 in the same direction as gear 28 but at a greater speed because of the smaller gear ratio between gears 31 and 38 as compared with the gear ratio between gear 28 and gear 39. Therefore sleeve 29 rotates faster than gear 28, although it rotates in the same direction as said gear, causing the spiral spring 32 to be wound up. The winding of spring 32, however, occurs in relatively small increments, and therefore the danger of over-winding said spring is minimized. As shaft 23 is being rotated by handle 25 to wind up the spring, gear 38 is allowed to rotate freely with respect to shaft 36 because of the yieldable engagement of ratchet disc 42 with the ratchet teeth 41 on the gear 38. After the spring is wound, the spring exerts a torque which tends to restore the gears 31 and 28 to their initial relative angular positions and this torque is transmitted by means of the gear 38 and its ratchet teeth 41 to the ratchet disc 42 and thence to the shaft 36, causing the gear 40 to drive the respective gear trains connected to the hour and minute pointers 53 and 50 around the clock's dial face 18. Said gear trains are arranged so that the minute pointer 50 moves twelve times as fast as the hour pointer 53 to provide the proper ratio of movement between the minute and hour hands of the clock.

The inertia and frictional losses of the clock above described in themselves will provide a regulating means causing the spring 32 to unwind at a substantially constant rate and eliminating the necessity of employing a conventional flywheel and hair spring to regulate the rate of rotation of the small driving gear 40. However, if very high accuracy is desired a conventional escapement mechanism including a flywheel and hair spring, as employed in ordinary timepieces, may be coupled to the shafts 36 in any suitable manner to provide absolute regulation of the rate of unwinding of the spring 32.

By employing the arrangement above described, the wear on the various moving parts of the movements is substantially equalized and excessive winding of the spring 32 is avoided. It will also be apparent that the cost of manufacturing a practical timepiece, as above described, will be substantially less than the cost of manufacturing timepieces of the prior art, inasmuch as the need for a flywheel and hair spring is avoided by employing the arrangement described herein.

While a specific embodiment of an improved movement for a timepiece has been disclosed in the foregoing description, it will be understood that various modifications within the spirit of

the invention may occur to those skilled in the art. Therefore it is intended that no limitations be placed on the invention except as defined by the scope of the appended claims.

What is claimed is:

1. In a timepiece, a frame, a wind shaft journaled in the frame, a first gear fixedly circumposed on the wind shaft, a sleeve rotatably arranged on the wind shaft and having one end spaced from the first gear, a second gear of a different size from the first gear concentrically arranged on the shaft and fixed to the sleeve, a spiral spring mounted on the sleeve and connected adjacent its outer end to the first gear, a shaft rotatably mounted on the frame parallel to and spaced from the wind shaft, a sleeve member rotatably disposed on the shaft, respective relatively small gears rigidly circumposed on the sleeve member meshing respectively with the first and second gears, whereby rotation of the wind shaft causes the first gear to rotate and causes the second gear to rotate in the same direction but at a different rate to wind the spring, a third gear fixed on the shaft, interengageable ratchet elements carried by the shaft and one of said relatively small gears for rotatively connecting the sleeve to the shaft, an hour pointer and a minute pointer rotatably mounted on said frame for rotation around an axis aligned with the axis of rotation of the wind shaft, and respective gear trains having different speed ratios carried by the frame and coupling said third gear to the hour pointer and the minute pointer.

2. In a timepiece, a frame, a wind shaft journaled in the frame, a first gear fixedly circumposed on the wind shaft, a sleeve rotatably arranged on the wind shaft and having one end spaced from the first gear, bearing means mounting said sleeve on the wind shaft, a second gear of a different size from the first gear concentrically arranged on the wind shaft and fixed to the sleeve, a spiral spring fixedly mounted on the sleeve and connected adjacent its outer end to the first gear, a shaft rotatably mounted on the frame parallel to and spaced from the wind shaft, a sleeve member rotatably mounted on the shaft, respective relatively small gears rigidly circumposed on the sleeve member meshing respectively with the first and second gears, whereby rotation of the wind shaft causes the first gear to rotate and causes the second gear to rotate in the same direction but at a different rate to wind the spring, a third gear fixed on the shaft, interengageable ratchet elements carried by the shaft and one of said small gears for rotatably connecting the sleeve to the shaft, spring means biasing said ratchet elements into engagement with each other, an hour pointer and a minute pointer rotatably mounted on said frame for rotation around an axis in alignment with the axis of the wind shaft, and respective gear trains having different speed ratios carried by the frame and coupling said third gear to the hour pointer and the minute pointer.
